UNITED STATES PATENT OFFICE.

LEE S. BURRIDGE, DECEASED, LATE OF NEW YORK, N. Y., BY FRANCIS O. BURRIDGE, EXECUTOR, OF NEW YORK, N. Y., ASSIGNOR, BY MESNE ASSIGNMENTS, TO UNDERWOOD TYPEWRITER COMPANY, OF NEW YORK, N. Y., A CORPORATION OF DELAWARE.

TYPE-WRITING MACHINE.

1,284,055.

Specification of Letters Patent.

Patented Nov. 5, 1918.

Original application filed September 30, 1915. Serial No. 53,220. Divided and this application filed February 27, 1917. Serial No. 151,173.

To all whom it may concern:

Be it known that LEE S. BURRIDGE, deceased, late a citizen of the United States, and late residing in the borough of Man-

5 hattan, county, city, and State of New York, invented certain new and useful Improvements in Type-Writing Machines, of which the following is a specification.

The present invention relates to ribbon-10 vibrating mechanism for typewriting machines. More particularly the invention relates to mechanism, of this character, in a typewriting machine in which the platen is carried on a frame shiftable between two 15 or more case-positions on the main frame.

An object of the invention is to have the ribbon-vibrating mechanism of such construction that it may be in large part mounted on the shiftable platen frame in a compact 20 and convenient manner; the parts being readily accessible for setting and assembling, simple in operation, and of inexpensive manufacture. A feature of the invention is a novel connection of the ribbon mechanism, 25 on the shiftable platen frame, to a universal bar, on the main frame, operable at type-strokes; the connection being flexible or capable of accommodating itself to the different case-positions of the platen frame, so 30 that the ribbon mechanism need at no time be disconnected from the universal bar. A feature of the invention is the construction and manner of shifting the platen frame, whereby the proper relations of the ribbon 35 mechanism to the platen are maintained in all case-positions of the platen, without complicated parts or movements.

One of the objects of the invention is a simple and novel ribbon-vibrating mechanism, shiftable with the platen between two 40 or more case-positions; and, in all case-positions, being adjustable, to effect a variable throw of a bichrome ribbon, so that one or another of the color zones thereof may be 45 presented to the printing point at the type-strokes; or so that the ribbon may be maintained silent at type-strokes, for stenciling. A feature of this mechanism is the manner in which the ribbon vibrator is supported for 50 oscillation at type-strokes, and in which this support is adjustable relatively to the vibrator to shorten or lengthen the effective

ribbon-throwing arm of the vibrator. Another feature is a device for locking the vibrator support in any adjusted position 55 thereof.

In a preferred form of the invention, the platen frame is shiftable substantially rectilinearly between case-positions, so that the platen and the ribbon-vibrating mechanism 60 both have practically the same movement, and maintain their relative positions. On the main frame of the machine is a rock shaft, connected to the universal bar, to be rocked by the latter at type-strokes. Pivotal 65 mounted on the shiftable frame are two levers connected by links to arms on the rock shaft. These links form a permanent and flexible connection between the ribbon mechanism on the platen frame and the universal 70 bar on the main frame; because, when the platen is shifted, the link merely rocks to another angular position or setting. There are, as usual, two ribbon spools, and each lever actuates a pawl and ratchet mechanism 75 at one of the spools, for turning that spool. The pawls and ratchets are arranged to drive the two spools in opposite directions, and hence, according to the direction of feed of the ribbon, when one mechanism is operative, 80 the other is inoperative.

One of the two levers operates the ribbon-feeding mechanism and said lever is also linked to the ribbon-vibrating mechanism to operate the latter. The vibrating mechanism 85 comprises a ribbon-carrier in the form of a vibratory arm through which the ribbon is threaded, and this arm is linked to an oscillatory plate. The link from the ribbon-feeding lever carries a pin in a slot in the 90 oscillatory plate, and this pin is linked to another pin in the same slot, which latter pin serves as the pivot on which the plate oscillates. The plate is supported and guided in its oscillatory movements by a pin 95 in another slot in the plate; and this supporting pin is carried by a finger-piece which may be set in different angular positions, to lift or lower the oscillatory plate with respect to the pivot pin thereof, so that the 100 effective vibrating arm may be lengthened or shortened, to change the throw of the ribbon-carrier, and thus to present one or another of the color zones of the ribbon to

the printing point. Another shift of the supporting pin removes the pin on the link which oscillates the plate from the slot in the latter, so that, when stenciling is to be done, 5 the plate and ribbon-carrier are silenced.

This application is a division of application No. 53,220, filed September 30, 1915 (patented December 4, 1917, No. 1,249,022).

Other features and advantages will here- 10 inafter appear.

In the accompanying drawings,

Figure 1 is a top plan view, partly broken, of the ribbon-vibrating mechanism, and of the frames on which the same is mounted.

15 Fig. 2 is a view in front elevation of the ribbon-carrier and of certain of the connections for vibrating the same; a part of the platen, the type-guide, and a ribbon-guide being also shown.

20 Fig. 3 is a view in cross-sectional side elevation through the machine frames, showing the ribbon mechanism and the connections to the same from the type-keys.

Fig. 4 is a view in side elevation of the 25 ribbon-vibrator, and of its connections to the ribbon-carrier, and to the lever by means of which it is actuated.

The platen 10 is journaled in a frame 11 which has letter-feed and return movement

30 on a frame 12. The frame 12 is connected to the main frame 13 by links 14 at each side thereof, and is shiftable up and down thereon between case-positions, of which there may be three, as shown and described in my

35 co-pending application for Letters Patent, Serial No. 52,594 filed September 27th, 1915.

The type keys 15 are on levers 16 fulcrumed on a blade 17 carried by the main frame. Each type key is held to its fulcrum, and is

40 also returned to normal position after each operation thereof, by a spring 18 which is attached at one end to a finger 19 on the key lever and at the other end at 20, to the rear of the key lever, and which is bent over

45 a plate 21 on the main frame, so that the spring, in tending to straighten itself, exerts an upward pressure on the key lever. A plate 22 also restricts movement of the key levers away from the blade 17. The key

50 lever operates in a slot 23 in a front plate 24 of the main frame; and the upper and lower walls of the slot determine the throw and normal position of the key lever. Each type key lever has a shoulder 25 thereon, adapted,

55 upon depression of the key, to engage and depress a universal bar 26 pivoted at 27 in arms 28 on the main frame. A suitable spring (not shown) returns the universal bar to normal position when the key is released, and a suitable stop (not shown) determines the normal position of the universal bar and other parts connected thereto.

To ears 30 on the side plates 31 of the shiftable platen frame 12, are secured cups 65 32, one at each side of the machine, to re-

ceive the ribbon spools 33 and 34. Journalled in ears of brackets secured to the side plates 31 of the platen frame, are shafts 35, onto each of which one of the spools is adapted to be placed for rotation therewith.

70 Fast to each shaft 35 is a hub 40 secured to a ratchet wheel 53, by means of which the spool is turned step by step at type-strokes. Loose on each shaft 35 is an arm 54; and pivoted to the end of the arm 54 is a pawl 56, held resiliently in engagement with the teeth of the ratchet wheel by a spring 57, for turning the ratchet wheel when the arm 54 is vibrated. Pivoted to the base of the cup 32 (see Fig. 1), and held resiliently to the 80 ratchet wheel by a spring 58, is a pawl 60 for holding the ratchet wheel when the pawl 56 is returning to normal position after each feed.

85 Each arm 54 has depending therefrom a pin 61 which lies between two prongs 62, offset horizontally on the end of a lever 63, pivoted at 64, at an intermediate point thereof, to the bracket ear. Pivoted connected to the lower arm of each lever 63 is a link 65, 90 the other end of which connects to an arm 66, fast to a rock-shaft 67, journaled in bracket arms 68, which are secured to a cross plate 69 of the main frame near each side thereof, (see Fig. 3). Also fast to the 95 shaft 67 is an arm 70, connected by a link 71 to the universal bar 26. Depression of the universal bar by a type key therefore rocks the shaft 67, to throw the links 65 and rock the levers 63, thus effecting a one-step 100 feed of the ribbon. The universal bar, in returning to normal position, also returns the levers 63 and pawl-carrying arms 54 to normal position. A preferred means for connecting the link 65 to the lever 63, and 105 one which permits of ready separation and union of the two, is shown in Fig. 3, comprising a pivot and spring on the link 65. It will be noted that the link 65 maintains the connection of the arm 66, on the main 110 frame, to the lever 63, on the platen frame, in all case-positions, and during the shift of the latter. A shift of the platen frame merely causes the lever 63 and link 65 to assume a different angular position, and the 115 pawl 56 to be moved slightly to a different set position on the ratchet wheel: the operation of the parts at type-strokes is not changed. The ribbon may be fed in either direction; and the direction of feed may be 120 reversed when desired.

Between the spools, and just to the left of a type guide 84 on the segment 85, at printing point, the ribbon is threaded through an eye or slot 86^a in a carrying arm 86. At the 125 right of the printing point, the ribbon is held and guided between two spring clips 87 and 88 secured to the platen frame. The clip 88 may also serve as a paper guide. The carrier 86 is vibrated at type-strokes, (el- 130

cept in stenciling), to present the ribbon to the printing point, and thereafter to return it to a normal position below the printing point. The carrier is shown as a strip of sheet metal turned on itself to have a part 39, by means of which it is braced for rigidity. The carrier is on a pivot pin 90 held in ears on a bracket 91 secured to the left-hand side plate 31 of the shiftable platen frame. 10 Its point of support thus maintains the same position with respect to the platen in all case-positions of the latter. The normal, or non-printing, position of the carrier, (shown in full lines in Fig. 2), is determined by contact of a stop finger 92 on the carrier against the side plate of the platen frame. For shifting the carrier at type-strokes, to the dotted line position in Fig. 2, to present the ribbon to the printing point, there is a link 15 93, one end of which hooks into a hole 86^b in the carrier, and the other end of which connects with a vibratory plate 94 on a bracket arm 95 secured to a cross plate 96 forming part of the shiftable platen frame. The bracket arm 95 may also be braced from the side plate 31 of the platen frame by a strip of metal 97. The plate 94 is slotted at 98 to engage a pin 99 on the bracket 95; and pivoted on the pin 99 is a link 100, pivotally connected by a pin 101 to a link 102. When the parts are set for printing, as distinguished from stenciling, the pin 101 also lies in the slot 98, so that reciprocation of the link 102 causes the plate 94 to be rocked, (for example, between the full and dotted line positions of Fig. 4), thereby causing the carrier to be moved up and down with the ribbon. A pin 103 on an arm 104 pivoted to the bracket 95, by engagement with another slot 105 in the plate 94, controls and guides the plate 94 in its vibratory movements. The link 102 is pivotally connected at 106 to the lever 63 which operates the ribbon-feeding mechanism, and which, it will be remembered, is connected to the universal bar 26 to be vibrated by the latter at type strokes. This connection, it will also be remembered, is maintained in all case-positions of the platen, and during the shifting operations. For connecting the link 102 to the lever 63, the latter may have an ear 116 offset from the end thereof. 20 The ribbon may be a bichrome ribbon, having, for instance, an upper black zone, and a lower red zone; and therefore requiring a longer throw at type-strokes to present the red zone, than to present the black zone, to the printing point. For stenciling, no throw of the ribbon is desired. There are therefore three settings of the ribbon vibrator, and the action thereof depends upon the position of the pins 99 and 101 in the slot 98 of the plate 94. This change of position of the pins is effected by shifting the plate on its supporting arm 95; and for this purpose, 25 the arm 104, which carries the pin 103 in the slot 105, forms part of a finger lever 107 pivoted at 108 to the bracket 95. If the lever 107 be moved to the right from Fig. 4 position, the pin 103 shifts the plate 94 downward and at the same time effects an angular shift of the same to the right, thereby causing the pin 101 to pass from the slot 98 into a slot 109, which, in this position of the plate, will extend in the direction of reciprocation of the link 102. Reciprocation of the link 102, when the plate 94 is so shifted, results in back and forth movement of the pin 101 in the slot 109 without vibration of the plate 94 or of the ribbon carrier; and 30 the parts are thus set in so-called neutral position for stenciling. If, on the other hand, the finger lever 107 is moved to the left from Fig. 4 position, the pin 103 will cause the plate 94 to be lifted, and at the same time shifted angularly to the left, leaving both pins 99 and 101 in the slot 98, but with a longer arm from the pin 101 to the point of connection of the link 93 to the plate, and also providing for a greater angular throw 35 of the plate 94 when the latter is vibrated. This last setting of the plate 94 therefore provides for a greater movement of the ribbon carrier at type-strokes than when the parts are set as in Fig. 4, and is the setting 40 for printing from the red zone of the ribbon. The Fig. 4 setting is the setting for printing from the black zone of the ribbon. 45 For locking the plate 94 in any of its settings, the finger lever 107 has an extension 110 with three recesses 111^a, 111^b, and 111^c in its edge. Adapted to engage the part 110 in any one of these recesses, according to the angular position of the lever 107, is a pin 112 carried by an arm 113, pivoted at 114 to the bracket 95. A spring 115, connecting the arm 113 to the bracket 95, holds the pin 112 in whichever of the recesses it registers with, and prevents accidental displacement of the lever 107 and plate 94. The pin 112 is cammed out by the teeth when the lever 107 is thrown to re-set the plate 94. 50 All parts of the ribbon-vibrating mechanism, and of the mechanism for setting the ribbon for different colors, and for stenciling, are seen to be carried by the shiftable platen frame, excepting only the connections from the lever 63 to the universal shaft; and even these last connections are at all times maintained unbroken. A shift of the platen frame, as pointed out, changes the angular position of the lever 63, and in so doing shifts the link 65 somewhat; and the link 65 in shifting, may change somewhat the setting of the plate 94. This last change is not sufficient, however, to affect the described operations of the mechanisms at type-strokes. 55

Variations may be resorted to within the scope of the invention, and portions of the improvements may be used without others.

Having thus described the invention, I
5 claim:

- plate oscillates, a link adapted to be rocked on said pin and carrying a second pin in said slot, means connected to said link for oscillating the same, means for supporting the plate with the pivot pin in desired position in said slot during oscillation thereof, a ribbon carrier connected to said plate, and means for shifting the plate in one direction relatively to its pivot pin to vary the throw of the ribbon carrier at type strokes, and in the other direction to cause said second pin to leave its slot so that the link may rock without movement of the plate and ribbon carrier.
15. 10. In a typewriting machine, an oscillatory plate slotted radially with respect to its pivotal point, a pin which projects into said slot and serves as the pivot on which the plate oscillates, a link adapted to be rocked on said pin and carrying a second pin in said slot, means connected to said link for oscillating the same, a third pin for supporting the plate in position on its pivot pin, the plate having a second slot to receive the supporting pin and to permit of oscillation of the plate thereon, a ribbon carrier connected to said plate, a pivoted carrier for the supporting pin, and means for setting said carrier in different angular positions to change the relative position of the plate and its pivot pin, so that the throw of the ribbon carrier at type strokes may be varied.
11. In a typewriting machine, an oscillatory plate slotted radially with respect to its pivotal point, a pin which projects into said slot and serves as the pivot on which the plate oscillates, a link adapted to be rocked on said pin and carrying a second pin in said slot, means connected to said link for oscillating the same, a third pin for supporting the plate in position on its pivot pin, the plate having a second slot to receive the supporting pin and to permit of oscillation of the plate thereon, a ribbon carrier connected to said plate, a pivoted carrier for the supporting pin, means for moving said carrier to different angular positions to change the relative position of the plate and its pivot pins, so that the throw of the ribbon carrier at type strokes may be varied, and a spring detent adapted to engage differently located retaining means on the carrier for the supporting pin, to lock the plate in any desired setting.
12. The combination with a ribbon-carrier, of an oscillating plate linked thereto, two linked pivots entering a slot in said plate, means for swinging one of said pivots about the other to oscillate the plate, and means for shifting said plate relatively to said pivots to vary the point to which the ribbon-carrier will be raised by the oscillation of the plate.
13. The combination with a ribbon-carrier, of an oscillating plate, a link between said carrier and said plate forming a toggle-joint with the plate, a pivot entering a slot in said plate for operating said toggle-joint, and a pin supporting said plate, adapted to be variably shifted to vary the point to which the ribbon-carrier will be raised.
14. The combination with a ribbon-carrier, of an oscillating plate, a link between said carrier and said plate forming a toggle-joint with the plate, a pivot entering a slot in said plate for operating said toggle-joint, and a pin supporting said plate, adapted to be variably shifted to vary the point to which the ribbon-carrier will be raised; said slot comprising an extension in which said pivot may operate idly.
15. The combination with a fixed pivot, of a link journaled on said pivot, an oscillating link, a floating pivot joining said first link to said oscillating link, a ribbon-carrier, a connecting link, an operating plate connected to said connecting link, extensions of both pivots extending into a slot in said operating plate, and means for variably supporting said plate along said fixed pivot, to vary the point to which the ribbon carrier will be raised.
16. The combination with a ribbon-carrier, of a slotted operating plate linked thereto, a fixed pivot about which said plate may rock entering the slot, a second pivot entering said slot for rocking said plate, means for supporting and operating said second pivot, and means for variably supporting said plate to vary the point to which the ribbon-carrier will be raised.
17. The combination with a ribbon-carrier, of an oscillating plate linked thereto, a fixed pivot entering a slot in said plate, an operating pivot also entering said slot, a third pivot entering a slot in said plate, adapted to shift said plate along the line of the other pivots, but permitting oscillation of said plate, and a finger-piece adapted to variably position said third pivot, to vary the position to which the ribbon carrier will be raised.
